W. McC. REID.
WATER SUPPLIED DISH MOP.
APPLICATION FILED JUNE 8, 1918.

1,298,787.

Patented Apr. 1, 1919.

UNITED STATES PATENT OFFICE.

WILLARD McC. REID, OF EVANSTON, ILLINOIS, ASSIGNOR TO REID-GEISLER MANUFACTURING CO., OF CHICAGO, ILLINOIS, A CORPORATION OF ILLINOIS.

WATER-SUPPLIED DISH-MOP.

1,298,787.

Specification of Letters Patent.

Patented Apr. 1, 1919.

Application filed June 8, 1918. Serial No. 238,809.

To all whom it may concern:

Be it known that I, WILLARD McC. REID, a citizen of the United States, residing at Evanston, in the county of Cook and State 5 of Illinois, have invented a certain new and useful Improvement in Water-Supplied Dish-Mops, of which the following is a specification.

The object of this invention is to provide 10 a mop of the general type described with a convenient continuous supply of water during the washing operation, thereby greatly assisting in removing the dirt from the dishes and to do this in such a manner that 15 the flowing water will not spatter in places where it is not wanted, particularly against the person or clothing of the operator of the device. The invention consists in a mechanical device capable of carrying out the 20 foregoing and other objects; which can be easily and cheaply made; which is satisfactory in operation, and is not readily liable to get out of order. More particularly, the 25 invention consists in the features and details of construction which will be hereafter more fully set forth in the specification and claims.

Referring to the drawings, in which similar numerals indicate the same parts 30 throughout the several views,

Figure 1 is a perspective view of mechanism illustrating this invention in its preferred form, in actual operation.

Fig. 2 is a sectional detail view through 35 the mop proper and water supply device.

Fig. 3 is a sectional plan view on the line 3—3, of Fig. 2.

Fig. 4 is a corresponding view on the line 4—4, of Fig. 2.

Fig. 5 is a perspective view of the various parts other than the mop material shown in Fig. 2, in dis-assembled position.

Fig. 1 illustrates the method of using the mechanism of this invention, in which the 45 operator uses one hand 10 to hold the plate 12, while with the other hand 14, rotating handle 15, a mop member 16 is rotated against the surface of the plate 12, water being continuously supplied to the under side of the mop 50 by a nozzle 18, fed by a hose 20, connected by divided pipe members 22 and 24, to hot and cold water faucets 26 and 28. By regulating these faucets the temperature of the water going to the mop may be varied. 55 The operation is conducted over a sink 30, or

other suitable receptacle designed to receive the flow of water as it drops from the plate 12 during the washing operation. In producing this invention, two very important facts have developed; first, that the discharge nozzle 18 must deliver water to the under side of the mop 16 in all positions of operation of the device, otherwise unpleasant and unsatisfactory spouting of the water from the mop will occur, and second, the 60 hose pipe 20 must be made of some fabric material instead of rubber, so that if it touches silverware lying in the sink 30 awaiting washing, these articles will not become tarnished by contacting rubber. In 65 order to always deliver the stream of water from nozzle 18 to the bottom of the mop 16, particularly while the same is being rotated by the hand 14 of the operator, it is necessary that the nozzle 18 be pivotally suspended from the mop handle 15, and this 70 is accomplished by the construction hereafter described.

Referring particularly to Figs. 2 and 5, the 75 mop member 16 is secured by a band 32 to a tubular member 34, provided with ventilating perforations 36, described, shown and claimed in my co-pending application filed herewith, Serial Number 238,810.

On the outer or handle end of this tubular member are screw threads 38 adapted to engage corresponding threads 40 on the inner end of a tubular sleeve 42, carrying a flange 44 and being split or slotted at 46. The nozzle member 18, heretofore described, 85 is provided with a supply pipe 48 which enters hose 20, heretofore described, and with a right angularly positioned plate or arm 50, perforated at 52, to pass over sleeve 42 to the position shown in Fig. 2. In assembling 90 the parts as shown in Fig. 2, this plate or arm 50 is followed by a washer 54, preferably but not necessarily held against rotation by projecting lugs 56 on its inner circumference, entering and traveling in slots 100 46 on opposite sides of sleeve 42, one such slot being shown in Fig. 5. The handle 15 has rigidly secured to it by a suitable pin 58 a tubular member 60 which fits over and frictionally engages sleeve 42, the pin 58 105 traveling in slots 46 so as to prevent rotation of parts 42 and 60 with reference to each other. This non-rotative frictional engagement of these parts permits the operator to adjust the tubular member and conse- 110

sequently the washer 54 longitudinally of sleeve 42 to arrange a proper amount of play by the member 50 between washer 54 and flange 44, heretofore described.

5 In order that the mechanism may operate properly, it is necessary that the diameter of opening 52 in member 50 be, as shown, substantially larger than the outside diameter of sleeve 42, with the result that the nozzle 18 always hangs free below the mop in the manner shown, regardless of the rotation of the mop by the operator. When it is desired to do so, the mop mechanism can be removed from the rest of the device without dis-assembling the other parts by simply rotating member 36 to disengage screw threads 38 from screw threads 40.

Attempts have heretofore been made to supply a mop of this general type with water delivered through the center or at some other point than the bottom, but without material success, owing to the fact that as the mop rotates, mop portions of the varying thickness are presented to the stream of water, with the result that parts of the water get out and spurt onto the user or in other directions which produce unsatisfactory results. By directing the stream of water from the nozzle 18 to the underside 30 of the mop only and to a comparatively limited portion of the underside, the entire body of the mop 16 hangs over the nozzle in all positions of rotation and thus practically prevents water escaping from the 35 mop during the operation of rotating the handle in washing dishes.

Having thus described my invention, what I claim as new and desire to secure by Letters Patent, is:—

40 1. In mechanism of the class described, a mop and a handle therefor, a water nozzle, means for conducting water to said nozzle, and means for suspending said nozzle from the mop handle swingingly connected with

the handle so that it will discharge water 45 against the mop while permitting rotation of the mop with reference to the nozzle.

2. In a device of the class described, a handle, a mop on the end of the handle, a collar in which the mop handle rotates a 50 nozzle carried by said collar and pointed toward the mop, and a hose pipe connecting said nozzle to a source of liquid supply, for the purposes set forth.

3. In a device of the class described, a 55 tube to which a mop is attached, a sleeve screw threaded upon said tube, a flange on the sleeve adjacent to the mop, a washer slideable lengthwise of said sleeve, a mop handle detachably connectible to said sleeve, 60 a nozzle connected to a source of liquid supply, and a plate supporting said nozzle interposed and loosely held in position on said sleeve between said flange and washer, so as to permit rotation of the mop with 65 reference to the nozzle, for the purposes set forth.

4. In a device of the class described, a tubular member carrying a mop, a sleeve threaded upon said tubular member, a flange 70 on the sleeve adjacent to the mop, a washer on the sleeve, a handle, a tube on the handle longitudinally slideable over the sleeve but non-rotatively connected thereto, a water nozzle mounted adjacent to the parts here- 75 tofore mentioned and pointed toward the mop, and means flexibly connecting the nozzle to the handle device, said connecting means being secured between said flange and said washer, for the purposes set forth. 80

In witness whereof I have hereunto subscribed my name in the presence of two witnesses.

WILLARD McC. REID.
